UNITED STATES PATENT OFFICE.

HENRY M. CASE, OF PHELPS, NEW YORK, ASSIGNOR OF ONE-HALF TO
SAMUEL M. LAWRENCE, OF SAME PLACE.

DESIGN FOR A CAN-BOTTOM.

SPECIFICATION forming part of Design No. 31,399, dated August 15, 1899.

Application filed July 17, 1899. Serial No. 724,201. Term of patent 3 $\frac{1}{2}$ years.

To all whom it may concern:

Be it known that I, HENRY M. CASE, a citizen of the United States, residing at Phelps, in the county of Ontario and State of New York, have invented and produced a new and original Design for a Can-Bottom, of which the following is a specification, reference being had to the accompanying drawings, forming part thereof.

Figure 1 is a perspective of a can-bottom. Figs. 2 and 3 are transverse sections of the same.

Numeral 1 denotes a cylindrical part having its greatest and smallest lengths at 2 and 3, respectively, which points in the upper periphery of the article are connected by a line curving outwardly and downwardly on each

side from point 2', as represented. At 4 the lines curve inwardly and their downward curve is accentuated. The cylinder is closed 20 by a concave plate, each point of the surface of which is situated in a line inclined directly toward the depression 5. This depression has an opening 6.

7 denotes a bead at the foot of the cylinder 1. 25

Having thus described my invention, what I claim as new, and desire to secure by Letters Patent, is—

The design for a can-bottom as herein shown and described.

HENRY M. CASE.
